UNITED STATES PATENT OFFICE.

JOHN H. FOX AND ALBERT E. EVANS, OF PITTSBURGH, PENNSYLVANIA, ASSIGNEES
TO PITTSBURGH PLATE GLASS COMPANY, A CORPORATION OF PENNSYLVANIA.

CAR-TRANSFER APPARATUS.

Application filed June 10, 1925. Serial No. 36,129.

The invention relates to a car transfer system designed particularly for handling the cars or tables employed in what is known as a straight away plate glass grinding and polishing operation. It has for its objects the provision of improved means for facilitating the shifting of the cars between a plurality of parallel tracks and for controlling the coupling and uncoupling of the cars by the operator of the shifting locomotive.

In the particular arrangement to which the improvement is applied, four parallel tracks are employed, the two central tracks being working tracks passing beneath a series of grinding and polishing runners, and the two outside tracks being return tracks for bringing the grinding tables or cars back to starting position on the working tracks. At each end of the four tracks is a transverse track carrying a transfer car, and upon the car is mounted a locomotive for pulling the grinding cars onto the transfer car and then pushing them off. A means is thus provided at each end of the four tracks for shifting the cars from any one of such tracks to any one of the other of such tracks. The improvement relates particularly to the means for positioning or indexing the transfer cars with respect to the four tracks, and to the means whereby the operator on the locomotive can control the coupling or uncoupling of the grinding cars, so that he can do this work without assistance from others, and without leaving the locomotive himself. This becomes important as the operation of the system is speeded up and the number of cars which must be shifted at each end of the system in a given time is increased. One embodiment of the invention is illustrated in the accompanying drawings wherein:

Figure 1 is a diagrammatic plan view showing the general arrangement of the system. Fig. 2 is a section on the line II—II of Fig. 1. Fig. 3 is a transverse section on the line III—III of Fig. 2. Fig. 4 is a section on the line IV—IV of Fig. 1. Fig. 5 is a longitudinal section on an enlarged scale on the line V—V of Fig. 1. Fig. 6 is a transverse section on the line VI—VI of Fig. 5. Fig. 7 is a partial end elevation and partial section of the transfer car. Fig. 8 is a detail plan view of certain of the parts shown in Fig. 7. Fig. 9 is a side elevation

on an enlarged scale at the position indicated by the line IX—IX of Fig. 1. Fig. 10 is an end elevation of the apparatus shown in Fig. 9. Fig. 11 is an end elevation of the transfer car looking at the end opposite to that of Fig. 7. Fig. 12 is an enlarged vertical section through the ends of a pair of grinding or work cars showing the coupling devices. And Fig. 13 is an end view of the shaft upon which the movable coupling member of the cars is mounted.

Referring to Fig. 1, A, B, C and D are the four parallel tracks comprising the system, A and B being the work tracks and C and D the return tracks. E and F are the transfer tracks, which carry the transfer cars G and H, and I, K, L, M etc. are the grinding or work cars or tables, to the upper surfaces of which are cemented the sheets of glass which are to be ground and polished. These cars are all the same in construction, but are given the different reference letters I, K, L and M for convenience in reference. Arranged in series over the work tracks A and B are a series of grinding and polishing runners beneath which the grinding cars or tables are slowly moved (from right to left), preferably by means of a rack and pinion drive (not shown). The cars or tables are moved along the tracks C and D (from left to right) by means of driven endless chains N and O. P and Q are the transfer locomotives for pulling the grinding cars onto the transfer cars and for pushing them off.

In operation, the glass to be surfaced is cemented upon the tables I at the right hand end of the track A and carried along this track beneath the grinders and polishers to the left hand end of the track, the cars being coupled together to form a continuous train. When a car reaches the left hand end of the track A, it is uncoupled and pulled onto the transfer car H by the locomotive Q, after which the transfer car is moved laterally on its track F until such track on the transfer car is in alignment with the track D, at which time the car carrying the glass sheet with its upper surface ground and polished, is pushed from the transfer car by the locomotive onto the track D and carried to the right along such track by the endless chain O. During such travel, the sheet is loosened from the car, and when the car reaches the right hand end of the track, it is picked up by a suitable vacuum frame,

turned over and seated upon the top of an empty car K on the track B where it is cemented in position preparatory to grinding and polishing the remaining rough side, 5 which is now up. The empty car on the track D, from which the sheet was removed, is now shifted by the transfer car G and its locomotive P to the track A, where it receives a new sheet of rough glass. This 10 completes the first half of the cycle.

The table K on the track B, to which the sheet whose progress is being traced is cemented, is now moved to the left as a part of a continuous train which moves to the left 15 along the track B and passes beneath a series of grinders and polishers corresponding to those arranged along the track A. When the car carrying the sheet reaches the left hand end of the track B, the surfacing 20 of its second side is complete, and it is removed by a vacuum frame and transferred to suitable racks, thus emptying the car or table upon which it had been seated. This empty car is now shifted by the transfer 25 car H and its locomotive Q to the track C, where it is engaged by the chain N and carried to the right hand end of the track. Here the grinding car is taken upon the transfer car G and shifted over to the track 30 B. It is here cleaned and made a part of the train ready to receive a sheet of glass and pass beneath the series of grinders and polishers, thus completing the second half of the cycle.

35 The grinding or work cars are constructed as more fully set forth in my application, Serial No. 687,705, filed January 22, 1924, and involve preferably a construction such as indicated in Fig. 12, and in which 1 and 40 2 are the cast body portions of the cars mounted upon the wheels 3, 3 and provided upon their under sides with the rack bars 4, 4. These cars are moved along the tracks A and B beneath the grinders and polishers 45 by means of driven pinions arranged at intervals along the line of travel of the cars and engaging the rack bars. The glass sheets which are to be ground and polished are secured to the upper surfaces of the 50 tables in any desired manner, but preferably by the use of plaster of Paris in a manner well known in the art. It is necessary that the upper surfaces of the cars as used in the continuous train shall present an unbroken 55 surface and to this end, the coupling devices are arranged so as to pull the ends of the tables tightly together with their upper surfaces flush with each other as indicated in Fig. 12. Each car has at one end a fixed 60 coupling hook 5 and at the other end a swinging coupling hook 6, and the cars are always so arranged that the fixed coupling hook of one car comes in opposition with the movable hook of the next car. With this 65 arrangement, the cars are automatically

coupled together when their ends are brought into abutting relation, the movable hook sliding over the fixed hook and dropping by gravity to interlocking position. The movable hook 6 is carried upon a trans- 70 verse shaft 7 whose ends project out past the sides of the car. On one side of the car, this shaft is provided with a handle or lever 8, while on the other side, it is provided with a handle or lever 9 (Fig. 9). In order 75 to pull the ends of the cars tightly together after the hooks are in coupled relation, the shaft 7 is provided with an eccentric portion. 10 which moves in a fixed bearing on the car, and the hook 6 is pivoted on the part 11 80 of the shaft so that a rotation of the shaft in a clockwise direction (Fig. 13) moves the hook 6 to the left, thus tightening the coupling. When the coupling is thus tightened, the handle 8 occupies the inclined position 85 indicated in Figs. 2 and 12, while the handle 9 at the other side of the car occupies the position indicated in Fig. 9.

The transfer cars G and H are similar in construction and are adapted to carry the 90 locomotives P and Q and one or more of the work cars. The tables are built up of commercial sections as indicated in Fig. 11 and are mounted upon the wheels 12. Each one is moved back and forth along this track 95 by means of a motor 13 driving the shaft 14 through the gears 15 and 16. The shaft 14 is mounted in suitable bearings and drives the shaft upon which one pair of wheels are keyed by means of the gears 17 and 18. 100 Each car is also provided with an indexing device for insuring a proper registration between the track on the car which carries the locomotive and the tracks A, B, C and D. This indexing mechanism is shown in 105 Figs. 7 and 8 and includes a pair of bars 19 and 20 slidably mounted in the framework of the car and provided with the rollers 21, 21 adapted to engage the indexing recesses 110 or notches 22, 22 carried by the cam rails 22^a and 22^a arranged in parallel with the tracks E and F upon which the transfer cars are mounted. The bars 19 and 20 are adapted to be reciprocated by the levers 23, 23 pivotally mounted on the brackets 24, 24 and operated from the motor 25 carried upon the car. The base 26 upon which the motor 25 is mounted is provided with a pair of bearings 27, 27 in which is mounted a counter-shaft 28 driven from the motor 115 through the intermediary of the gears 29 and 30. The ends of the shaft 28 on the outer sides of the bearings 27, 27 are threaded and extend through the nuts 31, 31. These nuts have pivoted thereto the yokes 12 32, 32, and telescopically arranged with respect to these yokes are a pair of yokes 33, 33 pivoted to the upper ends of the levers 23, 23. Between the ends of the yokes are the compression springs 34, 34. A nut 13

- screwed into the end of the yoke 32 and bearing against the spring serves as an adjusting means for varying the tension of the spring.
- 5 When the countershaft 28 is rotated in one direction, the nuts 31, 31 are drawn towards each other and the rods 19 and 20 are moved outward. When the direction of rotation of the shaft 28 is reversed, the nuts 31 are 10 moved away from each other and the rods 19 and 20 are moved toward each other. The parts controlling the indexing mechanism are so adjusted that normally the rollers 21, 21 yieldingly engage the came rails 22^a and 22^a, so that these rolls are forced into the notches or recesses 22, 22 when the track of the transfer car arrives in registration with any one of the tracks A, B, C and D. When it is desired to move the car from 15 one of these positions, the motor 25 is operated so as to retract the bars 19 and 20, thus rendering it easier for the motor 13 which moves the transfer car to shift from this indexed position to the next position of 20 the car. After the car has started from its position and the rolls 21 are out of the cam recesses, the motor 25 is operated to move the nuts 31, 31 inward and thus increase the spring pressure of the rolls 21, 21 upon the 25 cam tracks, so that when the car arrives in its next position, it will be positively stopped by the engagement of the rolls with the cam recesses provided the motor 13 (Fig. 11) has been stopped before such engagement. By 30 this arrangement, the car is very positively indexed in its various positions and no time is lost in getting it at its proper and exact position of registration with respect to the tracks A, B, C and D.
- 40 The work cars on the tracks C and D ordinarily become coupled together when they reach the right hand end of these tracks and while awaiting removal by the transfer car from these tracks to the tracks A and B.
- 45 When the locomotive moves off of the transfer car to engage one of these cars on the tracks C or D, it therefore becomes necessary to uncouple this car from the car to the left of it, and one of the features of my 50 invention consists in the provision of means whereby this may be automatically accomplished without the assistance of another workman and without the operator of the locomotive leaving his seat. The locomotive 55 itself comprises a body or frame 36 mounted on the wheels 37 and provided with the seat 38. It has at its front end a hook 39 with which the movable coupler hook 6 is adapted to engage automatically when the end of the 60 locomotive is pushed up against the end of the work car as indicated in Fig. 5. Each of the handles or levers 9 carried by the coupler shafts 7 for swinging the coupler members 6 is connected to a vertical lever 40 by means of a link 41 as indicated in Fig. 9,
- the levers 40 being pivoted to the car bodies at 42. The arrangement is such that when the lower end of the lever 40 is swung to the left, the lever 9 is swung to the right, which movement unlocks and lifts the coupler 70 member 6. This movement of the lever 40 to the left is accomplished by means of the stop member 43 which is fixed alongside of the track D and also alongside the track C at the right hand end of these tracks as indicated in Fig. 1. Therefore, when the locomotive is coupled to the car M as indicated in Fig. 9 and moves it, together with the next car M to the right to carry the car onto the transfer car, the lower end of the lever 40 75 is engaged by the stop lever 43 and the coupler between the two cars M, M is released so that the end car is freed from the rest of the train and can be moved onto the transfer car by the locomotive. However, it 80 may be necessary for the locomotive to move onto the track D to a point to the left of the stop lever 43 in order to reach the first car M, and in that case, the stop lever 43 would lie to the right of the lever 40 (nearest 85 to the locomotive), and on movement of the locomotive to the right again, the stop member 43 would engage this lever and uncouple the locomotive from the car. In order to avoid this difficulty, means are provided for 90 swinging the lever 43 away from the track as the locomotive moves past it on its way to the left. This arrangement is indicated in Figs. 9 and 10, the stop member 43 being mounted upon the shaft 44 carried in the 95 bearings 45, 45 and such shaft being provided at its end with a tripping lever 46. This tripping lever and the stop member 43 are held in normal position by means of a spring 47 arranged to yieldingly hold the 100 rod 48 (Fig. 10) to the right, such rod being pivoted at its end to the lever 46. A cam rail 49 is provided upon the side of the locomotive, so that as the locomotive moves to the left from the position shown in Fig. 9, 105 it engages the rounded end of the lever 46 and swings this lever and the lever 43 outward. When in this position, the member 43 is outside the line of travel of the levers 40, so that in case the first lever 40 is to the 110 left of the member 43 when the locomotive is coupled to the car, such member is held in this position during the movement of the locomotive to the right until the parts arrive at the position indicated in Fig. 9 at which 115 time the lever 46 is disengaged from the cam 49 and the member 43 swings back to normal position, so that it may engage the lever 40 when the cars are moved still farther to the 120 right.
- 125 After the work cars are shifted by the transfer car and its locomotive to the work tracks A and B, such cars are moved far enough along these tracks to couple them to the last car of the train which is being 130

moved ahead by the rack and pinion drive as heretofore described in connection with Fig. 12. These tables which are added are not, however, brought into tight engagement with the next table since in order to do this the handles 8 must be swung to the position indicated in Fig. 12 and Fig. 2 with a considerable degree of positiveness. In order to accomplish this function from the locomotive, the arrangement shown in Figs. 5 and 6 is employed. This arrangement includes a bar 52 carrying at each end a pair of plates 53, 53^a with the interposed wheels 54, 54 riding upon a track 55 in the form of an angle secured alongside the tracks A and B as indicated in Fig. 6. The plates 53 are provided with a transverse pin 56 preferably carrying a roller and adapted to engage the lower end of the handle 8 as indicated in Fig. 5 when the bar 52 and plates 53 secured thereto are moved to the left. After the parts arrive at the position indicated in Fig. 5 and the cars I—I become coupled, the bar 52 is moved to the left from the locomotive by means of the lever 57 in order to tighten the coupling operated by the lever 8. The lever 57 has a crank end 58 adapted to operate the pair of toggle links 59 and 60 through the intermediary of the link 61, the link 60 being pivoted to a fixed point on the locomotive at 62 and the link 59 being pivoted when the lower end of a fourth-link 63 which is pivoted at its upper end to the shaft 64 upon which the lever 57 is pivoted. The lower end of this link is adapted to engage a roller pin 65 extending between the plates 53^a so that when the lever 57 is moved to the position illustrated in Fig. 5, the lower end 63 is moved to the left, thus moving the bar 52 to the left and locking the coupling between the cars I—I by means of the lever 8.

Means are also provided for shifting the bar 52 to the right back to its starting point, such means including the bell crank lever 66 pivoted to the plates 53^a and occupying the position indicated in full lines in Fig. 5 when the bar 52 is in locking position. The horizontal arm of the bell crank lever 66 is provided with a roller 67 engaging the top of the rail 55, so that when the locomotive is moved to the right with the lower end of the link 63 in engagement with the vertical arm of the lever 66, such arm is held against rotation in a clockwise direction and the bar 52 is moved to the right with the locomotive, until the roller 67 on the lever 66 passes the inclined end 68 of the rail 55, at which time, the lever 66 rotates to the position indicated in dotted lines, so that on a further movement of the locomotive to the right, there is no further movement of the bar 52 to the right. The lever 66 is now out of the way of the lower end of the link 63, so that when the locomotive

carries a new car onto the track A, the lower end of the link 63 can pass over the lever 66 and engage the roller member 65 on the plates 53^a, thus moving the bar 52 again to the left to the position indicated in full lines in Fig. 5, the bell crank lever 66 being caused at this time to again assume the position indicated in full lines.

The hand lever 57^a serves to uncouple the right hand end of the last car I from the locomotive, such lever being pivoted upon the same shaft as the lever 57, and being adapted to secure the uncoupling of the member 39 carried by the locomotive from the coupler member 6 carried by the car I. This is accomplished by a cam lever 69 pivoted on the end of the locomotive and adapted to engage and lift the coupler 6 when the cam is swung in a clockwise direction. This swinging movement is accomplished by means of a link 71 connected at its right hand end to a crank arm 72 carried by the lever 57.

After the cars are locked together and the couplers tightened, as above described, they must still move a considerable distance before the racks 4 on the bottoms thereof are engaged by the pinions which move the train beneath the grinders and polishers. There is thus some danger that the couplers will become loosened, due to vibration or other causes and so prevent the tables from spreading slightly and interfering with the proper laying of the glass. To prevent this loosening and separating action, the guard rails 50 are provided, as indicated in Fig. 2 for engaging the lower ends of the levers 40 and holding them in the inclined locking positions indicated in Fig. 2. These rails have their ends inclined as indicated at 51 to give a camming action, as the handles 40 are engaged in case such handles are not fully moved to locking position before the rail is reached. These guard rails 50 extend along the tracks a considerable distance and serve to hold the couplers tightly in locked position until the pinions which engage the racks on the bottoms of the cars can engage such racks, after which it is not necessary that the couplers be held in locked position, since, with the rack pressing the table ahead and with the resistance of the train holding the car back, the car is held up against the car preceding by the drive of the pinion, so that there is no tension whatever upon the couplers and no couplers are in fact required from this point on.

It will be apparent from the foregoing description that the transfer system, including the locomotive and other apparatus, as described, permits of the shifting of the cars from the return tracks C and D to the work tracks A and B by the operator of the locomotive without any necessity of leaving his station upon the locomotive and without the

assistance of other workmen, the couplers at both ends of the car to be shifted being under the control of the operator of the locomotive, as heretofore described. The foregoing also applies to the shifting of the cars at the left hand end of the system from the work tracks A and B to the return tracks C and D, the operator of the locomotive being in control of the coupling and uncoupling operations and of the shifting of the cars without the necessity of leaving his station on the locomotive and without the requirement of assistance on the part of other workmen. In some cases, it may be desirable to shift two of the work cars as a unit, and this can be readily arranged for by having the transfer car of suitable size and by leaving the two work cars coupled together and shifting them as a unit, the proportions of the automatic controlling mechanism being modified as to length in order to handle this condition. When the cars arrive at the left hand ends of the tracks A and B, they are uncoupled by the rails 73, 73 (Figs. 1 and 4) which there engage the coupler handles 8 and swing them to the right, so that the locomotive can pull the end cars away from the trains and onto the transfer car H.

30. What we claim is:

1. The combination with a plurality of parallel tracks adapted to carry a series of cars or tables, a transfer track extending transversely of said tracks at one end thereof, a transfer car mounted on said track provided with a track adapted to receive a car from any one of said parallel tracks when the track on the transfer car is brought into alignment with such one of the parallel tracks, an indexing cam extending transversely of said parallel tracks provided with a recess for each of said tracks, a spring pressed indexing member carried by the transfer car and adapted to engage said recesses, and power means carried by the transfer car for retracting said member against the pressure of the spring.

2. The combination with a plurality of parallel tracks adapted to carry a series of cars or tables, a transfer track extending transversely of said tracks at one end thereof, a transfer car mounted on said track provided with a track adapted to receive a car from any one of said parallel tracks when the track on the transfer car is brought into alignment with such one of the parallel tracks, a pair of indexing cams extending transversely of the parallel tracks at opposite ends of the transfer car and each provided with a recess for each of said tracks, a pair of indexing members carried by the transfer car and spring pressed in opposite directions for engaging the recesses on the two cams, and power means carried by the transfer car for simultaneously

retracting the indexing members against the pressure of the springs.

3. The combination with a plurality of parallel tracks adapted to carry a series of cars or tables, a transfer track extending transversely of said tracks at one end thereof, a transfer car mounted on said track provided with a track adapted to receive a car from any one of said parallel tracks when the track on the transfer car is brought into alignment with such one of the parallel tracks, a pair of indexing cams extending transversely of the parallel tracks at opposite ends of the transfer car and each provided with a recess for each of said tracks, a pair of indexing members carried by the transfer car and spring pressed in opposite directions for engaging the recesses on the two cams, and power means carried by the transfer car for simultaneously retracting the indexing members against the pressure of the springs, said power means including a motor, and nut and screw mechanism for effecting the movements of said indexing members.

4. The combination with a plurality of parallel tracks adapted to carry a series of cars or tables, a transfer track extending transversely of said tracks at one end thereof, a transfer car mounted on said track provided with a track adapted to receive a car from any one of said parallel tracks when the track on the transfer car is brought into alignment with such one of the parallel tracks, an indexing cam extending transversely of said parallel tracks provided with a recess for each of said tracks, a spring pressed indexing member carried by the transfer car having a roller at its end adapted to engage said recesses, and power means carried by the transfer car for retracting said member against the pressure of the spring.

5. The combination in a transfer system including a plurality of parallel tracks, a transfer track extending transversely thereof, a transfer car on the track having a track adapted to be brought into alignment with said parallel tracks, and a plurality of work cars on the tracks with coupling means at their ends adapted to couple together when their ends are brought into abutting relation, of a locomotive mounted on the track on the transfer car and having coupling means for engaging the coupling means at the ends of the work cars, and means for uncoupling the end work car of the series from its abutting car operated by the movement of approach of such cars with respect to the transfer track, so that the locomotive can pull the work car thus uncoupled onto the transfer car.

6. The combination in a transfer system including a plurality of parallel tracks, a transfer track extending transversely there-

of, a transfer car on the track having a track adapted to be brought into alignment with said parallel tracks, and a plurality of work cars on the tracks with coupling means at their ends adapted to couple together when their ends are brought into abutting relation, of a locomotive mounted on the track on the transfer car and having coupling means for engaging the coupling means at the ends of the work cars, a swinging lever at the end of each car for releasing the coupler, and stop means alongside the parallel tracks adjacent the ends thereof arranged to engage said levers, and uncouple the end work car of the series from the next car as these cars approach the transfer track, so that the locomotive can pull the work car thus uncoupled onto the transfer car.

7. The combination in a transfer system including a plurality of parallel tracks, a transfer track extending transversely thereof, a transfer car on the track having a track adapted to be brought into alignment with said parallel tracks, and a plurality of work cars on the tracks with coupling means at their ends adapted to couple together when their ends are brought into abutting relation, of a locomotive mounted on the track on the transfer car and having coupling means for engaging the coupling means at the ends of the work cars, a swinging lever at the end of each car for releasing the coupler, stop means alongside the parallel tracks adjacent the ends thereof mounted for movement, so that in one position the stop means will engage said levers and in another position, will not engage the levers, and cam means on the locomotive for moving the stop means to nonengaging position, the said stop means being arranged to engage said levers as the cars approach the transfer track and secure the uncoupling of the end work car of the series from the next car, so that the locomotive can pull the work car thus uncoupled onto the transfer car.

8. The combination with a track, a plurality of cars mounted thereon and coupling means at the ends of the cars adapted to pull the cars into contact at their ends, of operating mechanism for each coupler, including a lever at the side of the car which tightens the coupling when swung in one direction, means for drawing the series of cars continuously forward, and a cam rail along the side of the track at the forward end thereof for engaging the levers and holding them in position to lock the couplers tightly during the first part of the travel of the cars along the track.

9. In combination in a transfer system including a track and a train of work cars thereon provided with couplers at their ends which interlock when the cars are

brought into abutting relation, and with means for operating such couplers to tighten them and draw the cars together, of a shifting locomotive for pushing other similar cars up against the train one after the other so that the coupler of each car interlocks with the one next ahead constituting a part of the train, and means operable from the locomotive for tightening the couplers after each car is coupled to the train.

10. In combination in a transfer system including a track and a train of work cars thereon provided with couplers at their ends which interlock when the cars are brought into abutting relation, and with means for operating such couplers to tighten them and draw the cars together, of a shifting locomotive for pushing other similar cars up against the train one after the other so that the coupler of each car interlocks with the one next ahead constituting a part of the train, a coupler on the locomotive for interlocking with the coupler on the end of the car which is being added to the train, means operable from the locomotive for releasing the coupler between the locomotive and the car which is being added to the train and means operable from the locomotive for tightening the coupler at the end of such car remote from the locomotive.

11. In combination in a transfer system including a track and a train of work cars thereon provided with couplers at their ends which interlock when the cars are brought into abutting relation, and with means for operating such couplers to tighten them and draw the cars together, of a shifting locomotive for pushing other similar cars up against the train one after the other so that the coupler of each car interlocks with the one next ahead constituting a part of the train, a coupler on the locomotive for interlocking with the coupler on the end of the car which is being added to the train, means operable from the locomotive for releasing the coupler between the locomotive and the car which is being added to the train, and means operable from the locomotive for tightening the coupler at the end of such car remote from the locomotive, said means for operating the couplers at both ends of the car being actuated independently by a pair of hand levers.

12. In combination in a transfer system including a track and a train of work cars thereon provided with couplers at their ends which interlock when the cars are brought into abutting relation, and with means for operating such couplers to tighten them and draw the cars together, such means including a lever at the side of each car, of a shifting locomotive for pushing other similar cars up against the train one after the other so that the coupler of each car added interlocks with that of the last one of the

train, an actuating device mounted at the side of the track for limited movement back and forth longitudinally thereof and adapted to engage said levers, and operating means carried by the locomotive for engaging said actuating device and moving the lever of the car next ahead to tightening position after the coupler of such next car has been engaged by that of the car which is being added to the train by the locomotive.

13. In combination in a transfer system including a track and a train of work cars thereon provided with couplers at their ends which interlock when the cars are brought into abutting relation, and with means for operating such couplers to tighten them and draw the cars together, such means including a lever at the side of each car, of a shifting locomotive for pushing other similar cars up against the train one after the other so that the coupler of each car added interlocks with that of the last one of the train, an actuating device mounted at the side of the track for limited movement back and forth longitudinally thereof and adapted to engage said levers, and a manually operated device carried by the locomotive for engaging said actuating device and moving the lever of the car next ahead to tightening position after the coupler of such car has been engaged by that of the car which is being added to the train by the locomotive.

14. In combination in a transfer system including a track and a train of work cars thereon provided with couplers at their ends which interlock when the cars are brought into abutting relation, and with means for operating such couplers to tighten them and draw the cars together, such means including a lever at the side of each car, of a shifting locomotive for pushing other similar cars up against the train one after the

other so that the coupler of each car added interlocks with that of the last one of the train, a coupler on the locomotive for engaging those on the cars, an actuating device mounted at the side of the track for limited movement back and forth longitudinally thereof and adapted to engage said levers and a manually operated device carried by the locomotive arranged to cause the release of the coupling between the locomotive and the car being shifted and to cause the movement of said actuating member to move the lever of the last car of the train so as to tighten the coupling between such car and the car which is being added to the train.

15. In combination in a transfer system including a track and a train of work cars thereon provided with couplers at their ends which interlock when the cars are brought into abutting relation, and with means for operating such couplers to tighten them and draw the cars together, such means including a lever at the side of each car, of a shifting locomotive for pushing other similar cars up against the train one after the other so that the coupler of each car added interlocks with that of the last one of the train, an actuating device mounted at the side of the track for limited movement back and forth longitudinally thereof and adapted to engage said levers, operating means carried by the locomotive for engaging said actuating device and through it moving the lever of the car next ahead to coupler tightening position, and means whereby a backward movement of the locomotive moves said actuating means back to its starting position.

In testimony whereof, we have hereunto subscribed our names this 6th day of June, 1925.

JOHN H. FOX.
ALBERT E. EVANS.
